(57) **CLAIM**

The ornamental design for a shade-providing sleeve, as shown and described.

DESCRIPTION

FIG. 1 is a front elevational view of a shade-providing sleeve showing my new design, the rear elevational view being a mirror image thereof;

FIG. 2 is a side view, taken from the left side of FIG. 1;

FIG. 3 is a side view, taken from the right side of FIG. 1;

FIG. 4 is a top plan view thereof;

FIG. 5 is a bottom plan view thereof; and,

FIG. 6 is a perspective view thereof.

The dotted line showing an arm and hand in FIG. 6 is for illustrative purposes only and forms no part of my design. The fragmentary cross hatch shading seen on the shade-providing sleeve is understood to represent fabric and the fragmentary stipple shading is understood to represent a contrasting material. Both are understood to repeat uniformly throughout the surfaces upon which they are shown.
